R. J. Craig,
ATTORNEY.

UNITED STATES PATENT OFFICE

LESTER H. MILES, OF LOS ANGELES, CALIFORNIA

SIREN ROTOR

Original application filed March 29, 1927, Serial No. 179,210. Divided and this application filed August 20, 1929. Serial No. 387,247.

This invention relates to a siren.

The general object of this invention is to provide an improved siren.

Another object of this invention is to provide a siren having peripheral flange sections and having curved vanes connected to the flange sections.

A still further object of the invention is to provide a siren having a hub and having a novel type of vane associated therewith.

A further object of the invention is to provide a siren having curved vanes.

Other objects of the invention will be apparent from the following description taken in connection with the accompanying drawings wherein:

Fig. 1 is a central longitudinal section of my improved siren showing the operating parts thereof.

Fig. 2 is a front view of the siren with the cover removed.

Fig. 3 is a view similar to Fig. 2 showing a slight modification.

Fig. 4 is a section through the modified siren taken on line 4—4 of Fig. 3.

Fig. 5 is a view similar to Fig. 2 showing a further modification, and

Fig. 6 is a section on line 6—6 of Fig. 5.

This application is a division of and addition to my co-pending application Serial No. 179,210, filed March 29, 1927.

Referring to the drawings by reference characters I have indicated my invention as embodied in a siren indicated generally at

10. As shown in the drawings the siren 10 comprises a casing indicated generally at 11.

This casing includes a hollow cylindrical body portion 12 and a cover plate 13 having a reduced hollow cylindrical hub or port member 14 thereon. The body 12 is also provided

40 on its outer periphery with a plurality of spaced apertures or ports 15 as clearly shown in Figs. 1 and 2, and a hollow boss 16, the function of which will be later described.

45 Mounted within the body 12 is a rotor 17. This rotor comprises a flat circular plate 18 provided at its center with a curved hub 19 and on its outer periphery with a plurality of short, arcuate spaced flanges 20. From one end of each flange 20 a vane 21 extends

inwardly. Each vane preferably comprises a short straight portion 22 and a longer curved portion 23 with the end of the portion 23 spaced from the base of the curved hub 19. The vanes 22 are preferably of uniform height throughout and they are curved outwardly so that the portion 21 is ahead when the rotor is rotated.

The construction is such that when the rotor 17 is revolved the vanes 21 force the air outwardly from the center through the apertures at the end of the flanges 20 and through the ports 15 of the casing. As the air is forced outwardly and the ports 15 are intermittently opened and closed by the rotor flanges 20 a loud noise is produced. The absence of connection between the vanes and the hub 19 and the shape and arrangement of the vanes, all combine to lessen the resistance as the rotor revolves while increasing the volume of sound produced.

The spacing of the ends of the vanes from the hub 19 also allows more air to enter the chamber between the vanes and thus a greater quantity of air may be forced out through the ports 15, thereby producing a much louder noise than if all the vanes ran direct to and were connected with the hub 19.

The rotor 17 is shown as mounted on a shaft 25. This shaft is provided with suitable bearings 26 and 27 fitted within the boss 16 of the casing with an enlarged flange 27. The shaft 25 and the rotor may be secured together as by a nut 28.

The rotor 17 is shown in the drawings as adapted to be driven by a disk 29 which may be adjustably mounted on the shaft 25 as shown. The rotor may, however, be driven in any other desired manner.

In Fig. 3 I show a siren wherein the casing 12' is similar to the casing 12. In this modification the rotor 30 has peripheral flange segments 31 thereon and a hub 32. A vane 33 is attached to each segment 31 between the body thereof. Each vane comprises a straight portion 34 and a curved portion 35 which terminates short of the hub 32.

In Fig. 5 I show a further modification wherein the rotor 40 is provided at its center with a hub 41 and on its outer periphery with

a plurality of spaced flange segments 42. From one end of each alternate flange 42 a vane 43 extends and joins the hub 41 and from one end of each of the remaining flanges 42 I provide a vane 44 which terminates intermediate the flange and the hub 41. The vanes 43 preferably have a cut away portion 45 (see Fig. 6) adjacent their juncture with the hub 41. The vanes 43 and 44 are curved outwardly opposite to the direction of rotation as clearly shown in Fig. 5.

Having thus described my invention, what I claim is:

1. In a siren, a casing, a cover for said casing having a central aperture therein, a rotor mounted in said casing, said casing having peripheral apertures therein, said rotor including a flat base plate having a rounded hub thereon, said base plate having spaced, annular, peripheral, flange sections thereon forming apertures therebetween, a vane extending from the end of each of said flange sections, each of said vanes comprising a short straight portion and a longer curved portion, 25 said vanes terminating short of said hub.

2. In a siren, a casing, a rotor in said casing, vanes on said rotor, a hub on said rotor, certain of said vanes engaging said hub and having a cut-away portion and other of said 30 vanes terminating short of said hub.

3. In a siren, a casing, a rotor in said casing, means for rotatably supporting said rotor, vanes on said rotor, a hub on said rotor, certain of said vanes engaging said hub, and 35 other of said vanes terminating short of said hub.

4. In a siren, a casing, a rotor in said casing, a plurality of vanes on said rotor, certain of said vanes each extending from a point near 40 the periphery of the rotor to a point near the axis of said rotor, the remaining vanes being shorter and terminating farther from the axis of said rotor.

5. In a siren, a casing, a rotor in said casing, 45 a hub on said rotor, a plurality of peripheral flange segments on said rotor, a vane on certain of said segments, each of said vanes being connected to said hub, said vanes having a portion cut away adjacent to the hub.

50 6. In a siren, a casing having a cover, a rotor in said casing, a hub on said rotor, a plurality of peripheral flange segments on said rotor, a plurality of vanes adjacent to said segments, each alternate vane terminating short of said hub, the remaining vanes being extended and connected to said hub.

55 7. In a siren, a casing, a rotor mounted in said casing, a hub on said rotor, a plurality of peripheral flange portions on said rotor, a plurality of vanes associated with said flanges, each alternate vane terminating short of said hub, the remaining vanes being extended and connected to said hub, said last mentioned vanes having a portion cut away 60 adjacent to the hub.

8. In a siren, a hollow casing having a peripheral flange, a cover for said casing having a central aperture therein, a rotor mounted to rotate in said casing, said casing having spaced peripheral apertures in said flange, 70 said rotor including a flat base plate having a central hub thereon, said base plate having annularly spaced, peripheral, flange sections thereon forming apertures therebetween, a vane extending from the end of each of said flange sections, each of said vanes including a curved portion with the inner end of the curved portion arranged to lead when the rotor is rotated, said vanes merging into said base plate short of said hub.

In testimony whereof, I hereunto affix my signature.

LESTER H. MILES.
